Patented Sept. 14, 1965

202,307

COIN OPERATED SOUND MOTION PICTURE PROJECTOR

Angelo Bottani, Milan, Italy, assignor to Società Internazionale Fonovisione S.P.A., Milan, Italy, a corporation of Italy

Filed May 5, 1964, Ser. No. 79,832

Term of patent 14 years

(Cl. D61—1)

FIG. 3.

FIG. 4.

FIG. 1 is a front perspective view of a coin operated sound motion picture projector showing my new design; FIG. 2 is a side perspective view thereof;

FIG. 3 is a perspective view looking from the rear and side thereof; and

FIG. 4 is a top view thereof.

I claim:

The ornamental design for a coin operated sound motion picture projector, as shown.
